IRVING I. ROSENTHAL, OF NEW YORK, N. Y.

ENVELOPE-FEEDING ATTACHMENT FOR TYPEWRITERS.

Application filed September 30, 1925. Serial No. 59,480.

This invention relates to improvements in typewriters, and has particular reference to an envelope feeding attachment therefor.

When addressing a number of envelopes considerable time is consumed in selecting an envelope from a stack and engaging said envelope with the platen of a typewriter preparatory to turning said platen to bring the envelope into proper position for addressing the same.

An object of the present invention is to effect a saving of time and labor in engaging an envelope with the platen of a typewriter by utilizing the movement of said platen to discharge an envelope from a magazine and toward said platen.

Another object is to actuate a rotary envelope discharging mechanism under the control of the platen to cause said mechanism to engage and momentarily grip an envelope in a magazine to withdraw said envelope therefrom.

The above and other objects will appear more clearly from the following detailed description, when taken in connection with the accompanying drawings, which illustrate a preferred embodiment of the inventive idea.

In the drawings—

Figure 1 is a fragmentary transverse section through a typewriter showing the invention applied thereto;

Figure 2 is a fragmentary sectional view illustrating the manner in which an envelope is engaged and discharged from the magazine;

Figure 3 is a plan view of the feeding attachment showing the same in operative position; and

Figure 4 is a front elevation thereof.

Referring more particularly to the accompanying drawings, in which portions of a typewriter sufficient to an understanding of the present invention are shown, the numeral 5 indicates the stationary top of a typewriter which supports the movable carriage 6. This carriage supports in turn the usual platen 7 with which is associated the guide 8 between which and the platen envelopes and letter paper are fed preparatory to typing thereon. The construction so far described is well known in the art and any further description thereof or of associated parts is deemed unnecessary to an understanding of the present invention.

The attachment of the present invention consists of a magazine 9 mounted in a for-

wardly inclined position, by means of a bracket 10, upon the carriage 6 so as to be movable therewith, the forward lower end of the magazine being disposed substantially in a vertical plane with the space between the platen 7 and guide 8, so that when an envelope is discharged from the magazine 9 in a downward direction, as indicated in the drawings, the same will enter said space and engage the platen 7 preparatory to being turned by the platen for addressing. The forward end of the magazine is open and provided along the vertical edges of the side walls thereof with narrow retaining flanges 11 which prevent the envelopes within the magazine from accidentally falling therefrom, but which, at the same time, permit of the foremost envelope being discharged downwardly past the bottom of the magazine by the mechanism later to be described. A follower 12 of any desired construction may be placed in the magazine at the upper end thereof so as to exert a constant downward pressure upon the envelopes.

The feeding mechanism is also supported upon the carriage 6 of the machine by means of standards 13 mounted at each end of said carriage and having bearings 14 at their upper ends in each of which one end of the stationary sleeve member 15 is secured. Extending through the sleeve members 15 and rotatable therein is a shaft 16 one end of which projects outwardly beyond one of the bearings and carries thereon a sprocket 17. This sprocket is engaged by an endless driving element such as a chain which also extends about another sprocket 19 secured on the adjacent end of the shaft 20 of the platen 7, so that when the platen is rotated a similar movement will be imparted to the shaft 16.

An ejecting member 21, in the form of an elongated plate, is mounted upon the shaft 16 by means of bearings 22 so as to rotate with said shaft. At the free longitudinal edge of said member the same is bent laterally to provide an extension 23 to which is secured an envelope engaging strip 24 made of rubber or any other suitable material which will frictionally engage the envelope to discharge the same downwardly from the magazine when the member 21 is rotated to the position shown in Figures 1 and 2.

To further assist in the ejection of an envelope from the magazine there is preferably associated with the ejecting member 21 a pair of gripping members 25. One of these

members is slidably supported at each end of the plate 21 for transverse movement relative thereto by means of a lug 26 and the outer end of said member 25 is provided 5 with a gripping jaw 27 which cooperates with the extension 23 of the plate 21 to momentarily grip the free edge of the flap of an envelope therebetween during its ejection from the magazine. The jaw 27 is normally 10 held in the retracted position with respect to the extension 23 by means of a retractile spring 28 one end of which is connected to the lug 26 and the other end to a pin 29 carried by the plate 21. In order to bring 15 the jaw 27 into engagement with the flap of an envelope at predetermined intervals during the rotation of the feeding mechanism, the sleeve 15 adjacent each member 25 has secured to its inner end a stationary cam 30 20 engageable with an extension 31 at the inner end of the member 25. Thus, as shown in Figure 2, when the feeding mechanism has reached the position where an envelope is engaged the cam 30 will project the member 25 outwardly and cause the jaw 27 thereof to engage the flap of an envelope between the same and the extension 23. This engagement continues until the extension 31 25 of each member 25 has passed over the enlarged portion of the associated cam, at which time the spring 28 will retract the jaw 27 and thereby free the envelope.

In operation, as the platen 7 is intermittently rotated by the line spacing mechanism 35 (not shown) of the typewriter, as for instance when addressing an envelope, the shaft 16 will also be rotated to bring the feeding mechanism including the members 21 and 25 to the position shown in Figures 40 1 and 2. The strip 24 now engages the foremost envelope in the magazine and due to pressure exerted upon said envelope the same will be forced downwardly past the bottom of the magazine as indicated in Figure 2. At the same time the jaws 27 of the members 25 will momentarily be engaged 45 with the flap of the envelope being ejected to assist in the discharge of said envelope from the magazine. While the envelope is 50 being discharged a slight forward pull will also be exerted thereon by reason of the rotary movement of the feeding mechanism and this pull will be sufficient to disengage the ends of the envelope from the flanges 55 of the magazine. After the envelope is free from the magazine, at which time the jaws 27 have been disengaged from the flap thereof, said envelope will fall to the dotted line position indicated in Figure 1, with the 60 normal upper edge of the envelope entering the space between the platen 7 and guide 8 so as to be in proper position for addressing upon further turning of the platen. This further turning of the platen produces rotation of the feeding mechanism so that by

the time an envelope in the machine has been addressed and is ready to be withdrawn from the typewriter another envelope will have been discharged from the magazine.

70

What is claimed is:

1. An envelope feeding mechanism for typewriters, including a magazine, and means controlled by the rotation of the platen of the typewriter to momentarily engage and grip an envelope in said magazine and thereby discharge the same from the magazine toward said platform, said means thereupon remaining out of engagement with the next succeeding envelope to 75 be discharged until said platen has completed a revolution.

2. An envelope feeding mechanism for typewriters, including a magazine supported above and movable with a typewriter, a 80 rotatable feeding mechanism operable to only momentarily engage an envelope during each revolution of said mechanism to discharge said envelope from said magazine in the direction of the platen of the typewriter 85 said mechanism thereupon remaining out of engagement with the next succeeding envelope to be discharged until the mechanism has completed a revolution, and a driving connection between said platen and said 90 feeding mechanism to operate the latter.

3. An envelope feeding mechanism for typewriters, including a magazine movable with the carriage of a typewriter, a feeding mechanism including a rotary feeding member 100 capable of engagement with an envelope in said magazine to discharge the same therefrom in the direction of the platen of the typewriter, means controlled by the rotation of said platen for rotating said feeding member, and gripping members supported by and movable relative to said feeding member and operable to momentarily grip the flap of an envelope between the same and said feeding member while the 105 envelope is being discharged from the magazine.

4. An envelope feeding mechanism for typewriters including a magazine movable with the carriage of a typewriter, a feeding mechanism including a rotary feeding member capable of engagement with an envelope in said magazine to discharge the same therefrom in the direction of the platen of the typewriter, means controlled by the rotation of said platen for rotating said feeding member, gripping members supported by and movable relative to said feeding member and operable to momentarily grip the flap of an envelope between the same 110 and said feeding member while the envelope is being discharged from the magazine, and cams for moving said gripping members relative to said feeding member and into engagement with said flap.

115

130

5. An envelope feeding mechanism for typewriters including a magazine supported above the carriage and platen of a typewriter, a rotatable shaft carried by said carriage, and a feeding plate rotatable with said shaft and extending radially therefrom and operable when said shaft is rotated to engage an envelope in said magazine to discharge the same therefrom in the direction of said platen, and means for rotating said shaft in synchronism with said platen.
6. An envelope feeding mechanism for typewriters including a magazine supported above the carriage and platen of a typewriter, a rotatable shaft carried by said carriage, a feeding plate rotatable with said shaft and extending radially therefrom and operable when said shaft is rotated to engage an envelope in said magazine to discharge the same therefrom in the direction of said platen, and means for rotating said shaft in synchronism with said platen.
7. An envelope feeding mechanism for typewriters including a magazine supported above the carriage and platen of a typewriter, a rotatable shaft carried by said carriage, a feeding plate rotatable with said shaft and extending radially therefrom and operable when said shaft is rotated to engage an envelope in said magazine to discharge the same therefrom in the direction of said platen, and a gripping member movable relative to said plate to momentarily engage the flap of an envelope while said plate is engaged with the envelope.
8. An envelope feeding mechanism for typewriters including a magazine supported above the carriage and platen of a typewriter, a rotatable shaft carried by said carriage, a feeding plate rotatable with said shaft and extending radially therefrom and operable when said shaft is rotated to engage an envelope in said magazine to discharge the same therefrom in the direction of said platen, a gripping member movable relative to said plate to momentarily engage the flap of an envelope while said plate is engaged with the envelope, and a cam fixed relative to said shaft for operating said gripping member.
9. An envelope feeding mechanism for typewriters including a magazine supported above the carriage and platen of a typewriter, a rotatable shaft carried by said carriage, a feeding plate rotatable with said shaft and extending radially therefrom and operable when said shaft is rotated to engage an envelope in said magazine to discharge the same therefrom in the direction of said platen, and a gripping member slid- 55
able on said plate to grip the flap of an envelope between the plate and gripping member while the former is engaged with the envelope.
10. An envelope feeding mechanism for typewriters including a magazine supported above and movable with the carriage of a typewriter, a feeding mechanism also movable with said carriage and including a rotary feeding member capable of engagement with an envelope in said magazine to 60
discharge the same therefrom in the direction of the platen of the typewriter, means controlled by the rotation of said platen for rotating said feeding member, gripping members associated with said feeding member and operable to momentarily grip the flap of an envelope between the same and said feeding member while the envelope is being discharged from the magazine, cams for moving said gripping members into engagement with said flap, and resilient means connecting said feeding and gripping members for retracting the latter from engagement with the envelope after having been operated by said cams.
11. An envelope feeding mechanism for typewriters including a magazine supported above the carriage and platen of a typewriter, a rotatable shaft carried by said carriage, a feeding plate rotatable with said shaft and extending radially therefrom and operable when said shaft is rotated to engage an envelope in said magazine to discharge the same therefrom in the direction of said platen, a gripping member slid- 65
able on said plate to grip the flap of an envelope between the plate and gripping member while the former is engaged with the envelope, and means to normally maintain said gripping member out of gripping relation 70
with said plate.

In testimony whereof I have affixed my signature.

IRVING I. ROSENTHAL.
